ARTER S. MOON, OF SAN FRANCISCO, CALIFORNIA.

ELECTRIC CONTACT DEVICE.

Application filed June 24, 1927. Serial No. 201,217.

This invention relates to improvements in electric contact devices, and has particular reference to an economical circuit making and breaking device. The device is particularly adapted to be employed for flashing a sign, such as a barber's sign where it is desired to flash different colored lights alternately.

The principal object of this invention is 10 to produce a device which is simple in construction and therefore economical to manufacture.

Another object is to produce a device which may be employed with the standard 15 barber pole having a motor drive connected therewith.

A further object is to produce a device of this character which can be readily installed in a small space.

20 Other objects and advantages will be apparent during the course of the following description.

In the accompanying drawings forming a part of this specification, and in which 25 like numerals are employed to designate like parts throughout the same,

Figure I is a side elevation of my device as the same would appear in a suitable housing,

30 Figure II is a top plan view of the contact disc and contact positioned thereon, and

Figure III is a perspective view on an enlarged scale of the manner of forming the movable contacts.

35 In places such as barbers' poles, it is common to employ a plurality of colored lights such as red, white and blue and to alternately flash these lights. The present method of flashing consists in employing an 40 electric motor having contacts thereon, which is a complicated mechanism and costly to purchase.

I have therefore produced a very simple 45 making and breaking device which may be supported on the customary clock motor employed to rotate the barber's pole and by so doing a single contact is rotated beneath a plurality of movable contacts, with the result that the various colored lights are 50 alternately flashed.

In the accompanying drawings wherein 55 for the purpose of illustration is shown a preferred embodiment of my invention, the numeral 5 designates a housing having a door 6 which provides access to the mechanism positioned therein. The numeral 7

designates the frame of a spring motor commonly known as a clock work.

This driving motor is adapted to drive a vertically positioned shaft 8 at a uniform speed. The speed is controlled by a ball 60 governor 9 which contacts a felt ring 11 thereby maintaining the speed of the motor uniform.

Positioned upon the vertical shaft 8 is an insulating disc 12. This insulating disc is 65 provided with two shoulders 13 and 14 and an up-standing central portion 16. Inclined surfaces extend from each of the shoulders around the up-standing portion 70 16 and are designated at 17 and 18. The inclined surface 17 has positioned thereon a contact 19 which is of considerable length so as to give considerable duration of illumination during the contacting period as will be 75 later described.

This contact 19 has an up-standing lug 21, which lug is bent horizontally as shown at 22 so as to form a centrally positioned contact. Supported upon the frame of the 80 motor 7 are brackets 23 and 24 which support an insulating disc 26, through the center of which extends the bared end of an ordinary insulated electric wire. This wire is designated by the numeral 27 and the bared 85 end by the numeral 28.

This bared end 28 is bent as at 29 so as to engage a centrally positioned contact formed upon the up-standing lug 21.

Similar electric wires 31, 32 and 33 have 90 their lower extremities bared and are secured to the periphery of the insulating disc 26 as by straps 34. As the lower extremities of each of these wires 31, 32 and 33 are bent in a similar manner, but one will 95 be described.

Referring to Figure III, it will be noted that the wire 33 has its lower end bared and bent at right angles as at 36 so as to form a horizontal portion 37. An eye 38 is now 100 formed midway of the horizontal portion, after which the wire is bent downwardly and upwardly as shown at 39 and 41, so as to form a U-shaped guide.

The movable contact which is adapted to 105 complete the circuit between the contact 19 and the wire 33, consists of a curved wire 42 having a flattened end 43, and a hooked end 44. The hooked end 44 engages the eye 37 while the main portion of the movable contact passes through the U-shaped guide 110 and has contact therewith.

The result of this structure is that when the device is in operation and the insulating disc 12 is rotated, the movable contact will first ride upon the inclined surface 18 and will drop from the shoulder 14 onto the contact 19, and after passing over the same, will drop from the shoulder 13 onto the inclined surface 18.

Due to the fact that the wire 27 is a common wire to all the lights in the circuit and due to the fact that the wires 31, 32 and 33 extend to their individual lights, when the movable contact engages the contact 19, a circuit will be established from the wire 27 through the central positioned contact 22 and thence through the up-standing lug 21 to the contact 19, and thence by movable contact 42 to the wire 37 and back to the opposite side of the circuit.

20 The fact that the movable contact rubs upon the opposite sides of the U-shaped guide assures electrical contact at all times, and due to the fact that the movable contacts operate by gravity there is no liability 25 of the device not functioning due to the breakage of springs and the like.

It will thus be seen that the device may be easily installed with a minimum amount of expense and that the device will function 30 as long as the motor operates.

It is to be understood that the form of my invention herewith shown and described is to be taken as a preferred example of the same, and that various changes relative to 35 the shape, size, material and arrangement of parts may be resorted to without departing from the spirit of the invention, or the scope of the subjoined claims.

Having thus described my invention, I 40 claim:—

1. In a device of the character described, a rotatable disc having shoulders formed thereon, a contact positioned between two of

45 said shoulders, an up-standing lug secured to said contact and having a portion centrally disposed with relation to said disc, a second insulating disc positioned above said first mentioned disc, and held stationary with respect thereto, a wire centrally positioned within said second mentioned disc, 50 and having its lower extremity engaging said central positioned contact, and a plurality of wires secured to the periphery of said second disc, each of said wires having a loop formed therein, and a movable contact engaging each of said loops and having their free ends supported on said first mentioned disc, for the purpose specified.

2. In a device of the character described, 55 a rotatable disc having shoulders formed thereon, a contact positioned between two of said shoulders, an up-standing lug secured to said contact and having a portion centrally disposed with relation to said disc, a second insulating disc positioned above said 60 first mentioned disc, and held stationary with respect thereto, a wire centrally positioned within said second mentioned disc, and having its lower extremity engaging said centrally positioned contact, and a plurality of wires secured to the periphery of said second disc, each of said wires having a loop formed therein, each of said wires 65 being further bent so as to form U-shaped guides, movable contact members, each of said contact members having a hooked end engaging one of said loops, the opposite end of said contact member being adapted to engage said contact on said first mentioned disc, said movable contacts being maintained in fixed position against lateral movement by said U-shaped guide.

70 In testimony whereof I affix my signature.

ARTER S. MOON.
